UNITED STATES PATENT OFFICE.

EDMOND A. HUSEBY, OF CHICAGO, ILLINOIS.

TRACKER-TUBE SUPPORT FOR PLAYER PIANOS.

Application filed February 5, 1927. Serial No. 166,090.

This invention relates to an improved tracker tube support for player pianos of that type wherein the music sheet rolls and tracker bar, and the roll-operating mechanisms, are mounted in a sliding drawer beneath the key bed of the instrument, and the player actions are fixedly mounted within or beneath the casing of the instrument in rear of the key bed. Since the drawer is drawn out for the insertion and removal of the music rolls, and is pushed in beneath the key bed when the instrument is playing, the tracker tubes connecting the tracker bar to the player actions of course have to be of sufficient length to accommodate the sliding movement of the drawer. If means were not provided for supporting the tracker tubes substantially mid-length thereof they would, when the drawer is closed, droop and present an unsightly appearance. One object of my present invention is to provide an improved tracker tube support which will effectively prevent drooping of the tracker tubes when the drawer is closed. Another object is to provide a tracker tube support of the character specified which will adequately support the tubes in both idle and playing position without any danger of creating kinks in the tubes which would choke the free flow of air therethrough. My invention is applicable to players of either the grand reproducing type or the upright type, and is well adapted to cooperate with player actions of the semi-unit type, such as that disclosed and claimed in Letters Patent to Albert A. Huseby No. 1,586,746, dated June 1, 1926, although capable of cooperation with other types of player actions.

Still other objects and attendant advantages of the invention will be apparent to persons skilled in the art as the same becomes better understood by reference to the following detailed description, taken in connection with the accompanying drawings in which I have illustrated one simple and practical embodiment of the principle of the invention, and wherein—

Fig. 1 is a front elevation of the key bed and drawer of a reproducing piano embodying my invention;

Fig. 2 is a vertical transverse section on an enlarged scale, showing the drawer in open position;

Fig. 3 is a view similar to Fig. 2 showing the drawer in closed position and also showing in vertical section a stack of player ac-

tions like those disclosed in the patent above identified;

Fig. 4 is a sectional plan view on a reduced scale taken on the line 4—4 of Fig. 3;

Fig. 5 is a fragmentary detail of one end of the tube-supporting reel and its support;

Fig. 6 is a cross-section of the tube-supporting reel on the line 6—6 of Fig. 5.

Referring to the drawings, 10 indicates a conventional showing of the key bed, and 11 designates as an entirety a drawer slidably mounted beneath the key bed 10 by any suitable means such as the tongue and groove supports indicated in Fig. 1 at 12. The bottom wall of the drawer 11 is, in the instance shown, provided with a longitudinal slot 13 by which the drawer may be opened by inserting the fingers therein, which avoids the presence of unsightly knobs on the front of the drawer for this purpose. In and lengthwise of the central portion of the drawer is mounted the usual tracker tube 14 supported at its ends by transverse partitions 15, and on either side of the tracker tube 14 are pockets for the reception of the usual music roll 16 and winding spool 17. On the outer sides of the partitions 15 are chambers to contain the music roll and winding spool motor, and the various controls of the instrument, with which the present invention is not concerned.

Suitably mounted in rear of the key bed and, in the case of a grand piano, suspended from the bottom board of the instrument is a stack of semi-unit player actions designated as entireties by 19, each provided at one end with a nipple 20. Extending between and connecting the nipples 20 of the player actions and the nipples 21 of the tracker tube 14 are the rubber tracker tubes 22, these latter being carried through suitable apertures in the vertical panel 23 beneath the rear edge of the key bed 10.

To the under side of the key bed 10 are secured a pair of spaced bearing brackets 24, in which is suspended with capacity of swinging movement a horizontal limb 25 of a bail-shaped rod, the depending limbs of which are shown at 26. In and between the limbs 26 approximately mid-length thereof is mounted on pivots 27 of the tracker tube reel. Generally described, this reel consists of an approximately circular member formed with a diametric slot through which the tracker tubes extend. In

its preferred form as herein shown it consists of a pair of inversely disposed parallel semi-heart-shaped bars 28 that are connected and spaced at their ends by cleats 29 secured to the opposed flat faces of the bars 28 as by screws 30; each of the cleats being adapted to receive the pivot stud 27, carrying a spacing washer 31. The lower ends of the bail arms 26 are pivotally connected by links 32 to a pair of lugs 33 attached to the under side of the drawer 11.

When the drawer is pulled out, the reel is shifted bodily from the position shown in Fig. 3 to that shown in Fig. 2; and at the same time the drag of the portions of the tubes between the reel and the player action rotates the reel through a half turn, unwinding the tubes therefrom, as shown in Fig. 2. When the drawer is pushed in, the reel is shifted bodily back from the position shown in Fig. 2 to that shown in Fig. 3, and at the same time the slack in the tracker tubes is wound on the reel by the reverse rotation of the latter effected by the winding action of a cord or tape 34 that is secured at one end as by screws 35 to the under side of the bail 10 and is wound around the reel and attached at its other end as by screws 36 preferably to one end of one of the cleats 29. The member 34 preferably consists of a thin steel tape having, in its natural condition, the form of a helical spring whereby, when the reel is shifted toward the front of the key bed to unwind the tracker tubes, the tape exerts a slight turning action on the reel in a clockwise direction, to that extent relieving the tracker tubes of the pull. Since, however, the friction of the reel in its bearings is practically negligible, and the reel is encircled by as many tracker tubes as there are keys on the piano, the pull on the individual tracker tubes is practically negligible, and an ordinary inelastic cord or tape 34 may be employed if desired.

It will be observed that the cross-sectional shape of the reel is such that all of the tube-bending surfaces thereof are well rounded, which avoids the danger of producing kinks or chokes in the tubes themselves. It will also be observed that the construction avoids any relative sliding movement between the tubes and the reel, thereby avoiding chafing and wear of the tubes. At the same time, in both open and closed positions of the drawer the tubes are supported in sufficiently elevated position to be out of sight.

The structure illustrated and described is illustrative of one simple and practical embodiment of the principle of the invention, but it is to be understood that specific changes and modifications in the structural details may be resorted to without departing from the principle of the invention or sacrificing any of the advantages thereof,

and hence the invention is not to be understood as limited to the specific structure disclosed but includes all such variations, modifications and mechanical equivalents as fall within the terms and spirit of the appended claims. 70

I claim:

1. In a device of the character described, the combination with a key bed, and a player action in rear of said key bed, of a drawer 75 slidable beneath the key bed, a tracker bar in said drawer, tracker tubes connecting said tracker bar with said player action, and a tracker tube supporting reel suspended from said key bed.
2. In a device of the character described, the combination with a key bed, and a player action in rear of said key bed, of a drawer 80 slidable beneath the key bed, a tracker bar in said drawer, tracker tubes connecting said tracker bar with said player action, a reel beneath the key bed on which the tracker tubes are wound, and a bail pivotally suspended from the under side of the key bed 85 in and between the arms of which said reel is journaled.
3. In a device of the character described, the combination with a key bed, and a player action in rear of said key bed, of a drawer 90 slidable beneath the key bed, a tracker bar in said drawer, tracker tubes connecting said tracker bar with said player action, a reel beneath the key bed on which the tracker tubes are wound, a bail pivotally suspended from the under side of the key bed in 95 and between the arms of which said reel is journaled, and means actuated by said drawer 100 for swinging said bail.
4. In a device of the character described, the combination with a key bed, and a player 105 action in rear of said key bed, of a drawer slidable beneath the key bed, a tracker bar in said drawer, tracker tubes connecting said tracker bar with said player action, a reel beneath the key bed on which the tracker tubes are wound, a bail pivotally suspended from the under side of the key bed in 110 and between the arms of which said reel is journaled, means actuated by said drawer for swinging said bail, and means for turning 115 said reel to wind the tracker tubes thereon when said drawer is moved to closed position.
5. In a device of the character described, the combination with a key bed, and a player 120 action in rear of said key bed, of a drawer slidable beneath the key bed, a tracker bar in said drawer, tracker tubes connecting said tracker bar with said player action, a reel beneath the key bed on which the tracker tubes are wound, a bail pivotally suspended from the under side of the key bed in 125 and between the arms of which said reel is journaled, means actuated by said drawer for swinging said bail, and a flexible mem- 130

ber anchored at one end and at its other end encircling and attached to said reel for turning the latter in a direction to wind the tracker tubes thereon when said drawer is moved to closed position.

6. In a device of the character described, the combination with a key bed, and a player action in rear of said key bed, of a drawer 19 slideable beneath the key bed, a tracker bar in said drawer, tracker tubes connecting said tracker bar with said player action, a reel beneath the key bed on which the tracker tubes are wound, a bail pivotally suspended from the under side of the key bed in and 15 between the arms of which said reel is journaled, means actuated by said drawer for swinging said bail, and a steel tape attached at one end to the key bed and at its other 20 end encircling and attached to said reel for turning the latter when the drawer is moved in one direction.

7. As a new article of manufacture, a tracker tube supporting reel formed with a transverse slot for the passage of the tracker 25 tubes therethrough.

8. As a new article of manufacture, a tracker tube supporting reel formed with a diametric slot for the passage of the tracker

tubes therethrough and with rounded peripheral surfaces on opposite sides of said 30 slot on which said tubes are adapted to be wound.

9. A new article of manufacture, a tracker tube supporting reel comprising a pair of parallel reversely disposed bars of 35 substantially semi-heart shape in cross-section, and spacing cleats between the end portions of said bars attached to the inner opposed faces of the latter, thereby forming a 40 diametric slot in said reel adapted to accommodate the passage of tracker tubes therethrough.

10. In a device of the character described, the combination with a key bed, and a player action in rear of said key bed, of a drawer 45 slideably mounted beneath said key bed, a tracker bar in said drawer, tracker tubes connecting said tracker bar to said player action, a bail pivotally suspended from said bed, a tracker tube supporting reel journaled in the arms of said bail, links connecting said bail to said drawer, and means for effecting a turning movement of said 50 reel from a sliding movement of said drawer.

EDMOND A. HUSEBY.
